(57) **CLAIM**

The ornamental design for a studded tumbler with lid, as shown and described.

DESCRIPTION

FIG. 1 is a top front perspective view of a studded tumbler with lid, showing my design;

FIG. 2 is a front elevational view thereof;

FIG. 3 is a top plan view thereof;

FIG. 4 is a bottom plan view thereof;

FIG. 5 is a cross-sectional view taken along line 5-5 in FIG. 1;

FIG. 6 is a partially enlarged cross-sectional view taken from FIG. 5;

FIG. 7 is a partially enlarged cross-sectional view taken from FIG. 5;

FIG. 8 is a detail view of a partial portion of FIG. 2;

FIG. 9 is a detail view of a partial portion of FIG. 2; and,

FIG. 10 is a detail view of a partial portion of FIG. 2.

The broken lines in the drawings illustrate cross-sectional and partial view indicia and form no part of the claimed design.
